UNITED STATES PATENT OFFICE

2,643,668

HOSE NOZZLE SHIELD

Albert J. Ackermann, Kirkwood, Mo., assignor to
Viko, Inc., Clayton, Mo., a corporation of Mis-
souri

Application December 27, 1948, Serial No. 67,539

3 Claims: (Cl. 137—379)

1

The invention relates to a shield for a nozzle used in dispensing gasoline or other fluids from a pump into the tank of an automobile or other container.

The main object of the invention is to prevent the nozzle from scratching or damaging the finish of the automobile should the nozzle accidentally contact it.

Another object is to cover with cushion material all portions of the nozzle likely to accidentally contact the automobile finish.

Another object is to provide a relatively inexpensive shield which may be applied to any nozzle in general use without modifying or machining the nozzle.

Another object is to form the shield in a substantially flat mold and then shape the shield to the contour of the nozzle guard as the shield is applied thereto and without damage to the shield.

Other objects will be apparent to those skilled in the art from the following description and accompanying drawings, in which:

Figure 1 is a perspective of a gasoline dispensing nozzle mounting a shield constructed according to the invention.

Figure 2 is a side view of the shield removed from the nozzle and drawn to enlarged scale, a part being sectioned.

Figure 3 is a transverse section taken approximately on the line 3—3 of Figure 2, and showing securing clips before application to the guard in solid lines, and showing the guard and the clips secured thereto in dot-dash lines.

Figure 4 is a view similar to Figure 2, but showing another form of the invention.

Figure 5 is a transverse section similar to Figure 3 and is taken approximately on the line 5—5 of Figure 4.

Figure 6 is a longitudinal section through the lower end of the nozzle guard and of the shield applied thereto and shows another means for securing the shield to the guard.

Figure 7 is a rear view of the lower end of the shield shown in Figure 6 and removed from the nozzle guard.

In Figures 1 to 3, a nozzle 1, such as is used on gasoline pump hose lines, includes a handle 2 and a control valve 3, operated manually by a lever 4. A guard 5 is rigid with and extends outwardly from handle 2 and pivotally mounts one end of lever 4. A dispensing tube 6 extends forwardly of handle 2.

A shield 7 of rubber-like material includes a body having a cylindrical terminal portion 8

2

applied over the forward end of dispensing tube 6 and normally surrounding a portion of the tube adjacent guard 5. A substantially straight elongated part 9 is formed integral with one end of collar 8 and is applied to the outer face of the guard.

The elongated part includes a channel section applied only to the straight portion of the guard and having its flanges 10 extending inwardly and overlying the side faces of the guard. A relatively thin connecting portion 11 between the channel and collar 8 is readily curved to the contour of the outer face of the guard when applied to the latter. With this arrangement channel flanges 10 are not distorted by bending during application to the guard with the likelihood of cracking.

The wall of collar 8 is relatively thick at 8a and the middle part of the wall is relatively thin. The thickened annular edges provide a close fit to the nozzle and avoid dirt, etc., being received within the terminal.

A pair of U-shaped metal clips 12 are embedded in the channel section and may be bent to engage the side and inner faces of guard 5 to maintain the shield assembled to the guard irrespective of variation in contours of the shield and guard. The end of the shield body opposite cylindrical portion 8 is notched at 13 to receive a support bracket on the pump (not shown) for hanging the nozzle handle when not in use.

The shield preferably is formed substantially flat with collar 8 extending from the body in one direction and with flanges 10 and clips 12 extending from the body in the opposite direction. The shield is bent to the contour of the guard as it is applied thereto and is not preshaped for one particular guard.

The shield shown in Figures 4, 5 corresponds generally to the shield shown in Figures 1-3, but flanges 22 at the edges of the shield are deeper and are curved inwardly at 24 to fit and grip the side and inner faces of the guard. Also, a rib 23 extends inwardly from elongated part 20 intermediate flanges 22 and has reentrant sides terminating in shoulders 23a. Rib 23 is received in a slot in the guard, the shoulders 23a engaging the guard to hold the shield to the guard. Preferably a metal clip 25 is embedded in the end of the shield and projects therefrom and is bendable, as clips 12 previously described, to the position shown in broken lines to hold the shield to the rear of the nozzle handle.

The shield shown in Figures 6, 7 is substantially the same as the shield shown in Figures

1-3 except that the rear end of elongated part 30 is curved around the nozzle guard and is secured to the guard by a spring 31, having a hook 32 engaging the guard and anchored at 33 to a metal plate 34 embedded in elongated part 30. Preferably plate 34 is positioned beyond the curve in elongated part 30 adjacent the plane lower portion of the guard. Elongated part 30 may include one or more metal clips 35 functioning similarly to clips 12 and 25 previously described.

The shield covers those portions of the nozzle likely to contact and scratch the automobile when dispensing gasoline into the automobile tank and prevents damage to the finish of the automobile. The shield is relatively inexpensive and may be applied readily to any ordinary nozzle.

The details of the construction may be varied substantially without departing from the spirit of the invention and the exclusive use of those modifications coming within the scope of the claims is contemplated.

I claim:

1. The combination of a gasoline pump dispensing nozzle having a discharge tube and a valve guard and a shield therefor comprising a relatively short collar terminal portion of rubber-like material surrounding the liquid nozzle dispensing tube, a relatively long flexible channel-shaped substantially flat strip of rubber-like material applied to the valve guard with one end merging with one annular edge of said terminal portion, and a bendable metal clip embedded in the other end of the strip and projecting lengthwise therefrom and folded over a guard element to secure the shield to the guard.
2. In a shield of cushion material for ready application to a fluid dispensing metallic nozzle,

zle, a relatively short ring-like collar, and a relatively long flexible strap-like part extending therefrom at right angles to the axis of said collar, flanges extending from the sides of said part substantially perpendicularly to the plane of said part with their edges turned inwardly towards each other and distortable transversely of the strap-like part, there being a longitudinal relatively stiff upstanding rib intermediate said flanges with laterally projecting shoulders.

3. The combination of a liquid dispensing nozzle including a dispensing tube and a valve housing and a guard having an outer face with upstanding side faces, there being a slot in said outer face, and a nozzle shield of rubber-like material having a relatively short collar portion at one end surrounding the dispensing tube, having an elongated part applied to the outer face of the guard, having reentrant flanges extending from said elongated part and engaging over the side faces of the guard, there being a rib on said elongated part extending substantially parallel to and intermediate said flanges and through said slot for securing the elongated part to the guard.

ALBERT J. ACKERMANN.
